Inventor:
Thomas R. Kondrat,
Attorney.

UNITED STATES PATENT OFFICE

MATHIAS R. KONDOFF, OF LOWER MERION TOWNSHIP, MONTGOMERY COUNTY, PENNSYLVANIA, ASSIGNOR TO THE LOX SEAL CORPORATION, OF BROOKLYN, NEW YORK, A CORPORATION OF NEW YORK

ART OF TAGGING

Application filed November 10, 1927. Serial No. 233,242.

My invention is an improved hanger primarily adapted for the attachment of price tags, identification tickets or seals to merchandise or the like so that the attached devices cannot be accidentally disengaged or intentionally removed without the destruction or mutilation thereof. A leading object of my invention is to provide such hangers with retaining or locking hooks which, when inserted in the pocket of a tag or the like, cannot be unbent or straightened by a pull on the hanger or tag, thereby avoiding the necessity for using excessively hard and expensive wire to prevent such straightening and detachment of the hanger. A further object of my invention is to so shape the retaining hooks that when their ends are brought together their bodies will form humps or shoulders projecting from the hanger legs or shanks and preventing withdrawal of the hanger legs from a tag pocket even though the hook ends be brought simultaneously into registration with the aperture of the tag pocket.

These objects are preferably attained by forming a hanger of resilient wire bent in an arc to form an apex with shanks or legs projecting therefrom and terminating in hooks bent backwardly therefrom, crossing the legs, and forming juxtaposed closed eyes or loops. The free ends of the hooks diverge from one another and project from the sides of the legs opposite the loops. When the hooks are inserted in a tag pocket, the projecting ends first contact with the top of the pocket when the hanger or tag is pulled, and consequently the force tends to further bend and diminish the loops instead of straightening the bends connecting the legs and hooks. If the points of the projecting ends are brought together and into registration with the pocket aperture, as for instance by turning the tag at right angles to its normal position and squeezing the walls, the bodies of the hooks are forced outwardly from the hanger shanks and form humps or shoulders preventing withdrawal of the hanger.

In some cases, I may merely bend the hooks so as to form humps or shoulders when their

ends are brought together, without forming closed loops preventing unbending of the joint between the hooks and shanks. In either case, the hooks preferably each have a length exceeding the distance between the aperture and lateral edges of the tag pocket so that the hooks cannot be unbent without rupturing the pocket walls.

The characteristic features and advantages of my improvements will more fully appear from the following description and the accompanying drawings of illustrative embodiments of my invention.

In the drawings, Fig. 1 shows a hanger embodying a preferred form of my improvements inserted in a fabric to which a tag is to be affixed; Fig. 2 illustrates the positions of the hanger members and a tag when a tag is being telescoped on the hanger; Fig. 3 is an elevation of a tag which has been fully telescoped on the hanger and is permanently secured thereby to a fabric; Fig. 4 is a fragmentary sectional view illustrating the position assumed by the hanger members when it is sought to pull the tag from the hanger; Fig. 5 is an exaggerated illustration of the positions assumed by the hanger members when the tag is turned transversely to the hanger and the points of the hanger are squeezed together with a view to withdrawing the tag therefrom; Fig. 6 illustrates a modified form of hanger with a tag thereon; Fig. 7 is an exaggerated illustration of the position assumed by the hanger of Fig. 6 when it is sought to withdraw the tag by squeezing the points of the hanger hooks together after turning the tag transversely to its normal position; Fig. 8 shows a slightly modified form of hanger in a slightly modified form of tag; and Fig. 9 shows a hanger having curved hooks.

My improvements are particularly adapted for use with an integral, substantially flat tag formed from a suitably shaped and printed blank of paper or other sheet material which is apertured and scored or embossed so that when the laminae thereof are folded over and secured together by an adhesive the resultant tag A contains a pocket B with a substantially flat top C apertured at D, and, if de-

sired may be reenforced around the aperture with a washer or eyelet. The portions of the tag surrounding the pocket B are firmly glued together so that the pocket is closed excepting for the aperture D. It will, however, be understood that other forms of tags or seals having closed pockets may be used with my improved hanger, and that the term tag is used herein generically as meaning any 10 analogous device, such, for instance, as a seal.

As illustrated in Figs. 1 to 5 inclusive, my improved hanger is preferably formed of resilient, moderately hard wire bent to form a curved apex or top 1 having legs or shanks 15 2 and 3 projecting therefrom and spread thereby. The lower end of each shank is bent back upon itself in the general direction of the apex and on a curve or angle such that a portion of the resultant upturned hook 20 crosses the shank and has its end projecting from the side of the shank opposite the curved section connecting the hook and shank. Preferably the joints 4 and 5 at the bottoms of the shanks are bent at such angles 25 as to provide straight hook sections 6 and 7 normally substantially parallel with the respective shanks 2 and 3 and having bent therefrom at sharp angles the prongs 8 and 9 which cross and preferably press against 30 the shanks 2 and 3 so as to form closed loops. The ends of the members 8 and 9 are sharpened to readily penetrate the fabric F and preferably the prong 8 bears against one side of the shank 2 and the prong 3 bears against 35 the opposite side of the shank 3 so that the prongs will not interfere with one another when the shanks are pressed together.

To insert the hanger in a tag A, the legs 2 and 3 are pressed together, as in Fig. 2, and 40 pushed through the opening D. The shanks and hooks readily yield sufficiently for the passage of the prongs 8 and 9 and the parts assume within the pocket the positions illustrated in Fig. 3. Should an attempt be 45 made to pull the hanger from the pocket, the parts assume the positions illustrated in Fig. 4, which prevents the straightening out of the hooks since the greater the strain on the hanger the tighter the curved sections 4 and 5 are bent. If it is sought to get the points 50 of the hanger into registration with the aperture D, as for instance by turning the tag at right angles to its normal position and squeezing on the pocket walls to bring the 55 points together, this results in forcing outward the members 6 and 7 to form shoulders 10 and 11 which effectually prevent withdrawal. For facilitating the insertion of a hanger into a fabric F one or both the hooks 60 may have the prongs thereon bent outwardly from instead of crossing the shanks. For instance, as illustrated in Figs. 6 and 7, the hanger shanks 2 and 3 have the hooks 6a and 7a bent outwardly and instead of having 65 the prongs 8a and 9a crossing the shanks

they project outwardly therefrom. When it is sought to withdraw the hanger from the tag by pressing the points into registration with the aperture D, the parts assume the positions shown in Fig. 7 and form shoulders 70 preventing withdrawal of the hanger.

As illustrated in Fig. 8, the hanger may have one shank 2 bent to form the hook 6 with a prong 8 crossing the shank 2 and have the other shank 3 bent to form the hook 7a 75 with a prong 9a diverging from the shank 3. This construction facilitates threading the hook 7a through the fabric, the hooks 6 and 7a form projections or shoulders preventing extraction of the hanger by squeezing the 80 ends of the prongs into registration with the tag pocket aperture, and the prong 8 turns the shank 6 around the joint 4 and prevents the straightening of the hanger by pulling. The tag pocket B' in the construction shown 85 in this figure is formed below the top of the tag by embossing recesses in the tag laminae before uniting them and preferably during the printing thereof. The aperture D' for the passage of the hanger is formed in the 90 side of the recess.

As illustrated in Fig. 9, the hooks 6b, 7b at the ends of the shanks 2 and 3 may be curved so as to intersect the shanks instead of being bent at an angle as in the other examples. 95

In all the embodiments of my invention, but particularly when using the form of hanger shown in Figs. 6 and 7, the length of the hook is preferably greater than the distance from the aperture D to the side edge of the pocket so that any attempt to unbend the hooks will be checked by the engagement of their ends with the pocket walls or if persisted in will cause the hook ends to rupture 100 the pocket walls. 105

Having described my invention I claim:

A fastening device for unwithdrawable passage through a wall having a relatively minute aperture, said device comprising a wire bent to form legs, each leg being bent back upon itself to form a hook section, each hook section extending in a direction substantially parallel with its associated leg and having its free end bent at an angle to cross 110 its associated leg. 115

In testimony whereof I have hereunto set my hand this 8th day of November, 1927.

MATHIAS R. KONDOLF.
